UNITED STATES PATENT OFFICE.

JOSEPH A. STANSBURY, OF LOS ANGELES, CALIFORNIA.

GRINDING-WHEEL-SHARPENING DEVICE.

1,245,814.

Specification of Letters Patent.

Patented Nov. 6, 1917.

Application filed June 16, 1917. Serial No. 175,109.

To all whom it may concern:

Be it known that I, JOSEPH A. STANSBURY, a citizen of the United States, residing at Los Angeles, in the county of Los Angeles 5 and State of California, have invented new and useful Improvements in Grinding-Wheel-Sharpening Devices, of which the following is a specification.

My invention relates to improvements in 10 grinding-wheel sharpening devices and more particularly to devices for truing the sharp edges of the grinding wheel as for glass grinders or cutters; and the objects of my improvements are, to provide an oscillating 15 movement for the diamond so as to bring the diamond to both sides of the sharp edge of the grinding wheel; to provide an adjustable stop so as to allow a setting of the oscillating movement to procure a certain surface 20 on each side of the grinding wheel to be sharpened; to provide a second oscillating movement at right angles to the first oscillating movement incorporating a diamond carrying lever, the diamond on the lever 25 passing by this oscillating movement over the sides of the grinding wheel in an angle set by the adjustable stop in combination with the first named oscillating movement; the invention consisting in the construction, 30 combination and arrangement of devices hereafter more fully described and claimed, and illustrated in the accompanying drawing, in which—

Figure 1 is a side elevation of my device, 35 partly in mid-section.

Fig. 2 is a detail side elevation of the diamond carrying lever of my device.

Fig. 3 is a horizontal cross section on line 40 3—3 of Fig. 1.

Similar numbers refer to similar parts throughout the papers.

In Fig. 1, 4 designates a grinding wheel for producing cut-glass and for similar purposes, near which my attachment is used. 45 A diamond 5 is mounted on a lever 6, which is swingably mounted on the frame 7 by the pivot 8. The lower extension 9 of the lever terminates in a section of a bevel-gear 10, which engages with the bevel gear pinion 11. 50 The pinion 11 is secured to the shaft 12 by the key 13. The shaft 12 is provided with an enlargement 14 near the pinion forming an engaging member turnably journaled in a bearing member 15, provided on the frame 55 7. A friction member 16 is disposed within

the bearing member 15 of the frame holding the shaft 12 engaged with the frame to a suitable extent, as will later on be described. The shaft 12 extends downwardly below the base plate 17 having a gear 18 secured to the lower end by the key 19. A standard 20 is provided on the base plate forming the bearings 21 and 22 for the shaft. The lower end 23 of the frame terminates in a bent end 24, having a hole surrounding 60 the standard at the lower end near the base plate. A locking member 25 is secured to the base plate engaging slidingly over the end 24 of the frame holding the frame in position but allowing an oscillating movement of the frame around the standard 20. An adjustable lever 26 is pivotally mounted on the base plate at 27 having extension ends 28, see Fig. 2, projecting into the path 65 of the oscillating frame 7, thereby forming 70 stops for the oscillating movement, the edge 29 of the frame 7 hitting the extension end 28 of the adjustable lever when the frame comes to the position indicated at 30 in dotted lines, while the edge 31 will hit the 75 extension end on the opposite side of base plate 17 when the frame oscillates to that side. Pivotally connected to the lower end 32 of the adjustable lever is the screw rod 33, which is operated by the nut 34, the nut 80 being turnably disposed in the block 35 resting with the shoulder 36 against the block 35 from one side while the farther end 37 of the nut is slightly rolled or riveted 85 over the other side of the block holding the 90 nut turnably within the block.

A turning of the nut 34 causes the rod 33 to move to one or the other side, this causing the adjustable lever 26 to tilt correspondingly to one or the other side thereby 95 setting a stop to the oscillating movement of the frame 7, in Fig. 2 of the drawing, the lever being shown to allow the oscillating of the frame to a position about at right angles to each other at the stopping points on the opposite sides, but it will easily be understood that by the adjusting of the screw rod 33 any desired position may be obtained.

An operating lever 38 is pivotally mounted between the block 35 and the base plate around an extension end 39 of the block extending beyond the pivot support terminating in a gear segment 40. The gear segment 40 engages with the gear 18. 105 110

It will easily be understood that the lever 38 may be connected to a moving part of the grinding mechanism thereby receiving its motion, swinging back and forth, and this motion is naturally transmitted by the gear segment 40 on the lever 38 to the gear 18 on the shaft 12.

Since the shaft 12 turns freely in the bearings 21 and 22 of the standard on the base plate, but, by the friction member 16 within the bearing 15 of the frame, is engaged to a certain extent with the frame, the whole frame together with the shaft 12, bevel gear pinion 11, bevel gear segment 10 and the diamond carrying lever 6 is oscillated around the standard 20 until the frame 7 comes to engagement with one of the extension ends 28 on the adjustable lever 26 when the motion of the lever 38 transmitted to the gear 18 and shaft 12 will overcome the slight friction between the friction member 16 and the engaging member 14 on the shaft thereby turning the shaft with the engaging member 14 and the bevel gear pinion 11 further to a suitable extent so as to cause the bevel gear segment 10 with the diamond carrying lever to swing around the pivot 8. The frame standing in a desired position set by the adjustable lever 26, as described in relation with Fig. 2, will naturally cause the diamond carrying lever 6 to pass over the edge of the grinding wheel 4 in such desired angle while swinging on the pivot 8 as described above.

Having accomplished the truing of one side of the grinding wheel edge, it will easily be understood that the motion of the lever 38 can be reversed by a suitable connection on the grinding mechanism thereby procuring a similar action for the truing of the other side of the grinding wheel edge.

Having thus described my invention, I claim:

1. A device of the class described comprising a frame having means for oscillating movement in a suitable plane, a diamond carrying lever mounted on the said frame having means for oscillating movement in a plane at right angles to the first named plane, operating means engaging with the diamond carrying lever, and a friction member inserted between the operating means and the frame.

2. A device of the class described comprising a frame having means for oscillating movement in a suitable plane, an adjustable stop mounted near the frame in the path of the oscillating movement of the frame, a diamond carrying lever mounted on said frame having means for oscillating movement in a plane at about right angles to the oscillating movement of the frame, operating mechanism engaging with the diamond carrying

lever, and a friction member inserted between the operating means and the frame.

3. A device of the class described comprising a base plate having a standard projecting upwardly provided with a bore, a shaft mounted turnably in the bore of the standard, a gear keyed to the one end of the shaft, a bevel gear pinion keyed to the opposite end of the shaft, an engaging member provided near the bevel gear pinion on the shaft, a frame turnably mounted on the standard near the base plate having a bearing provided near its middle turnably fitting over the engaging member on the shaft, a friction member disposed into the bearing of the frame slidably engaging the frame with the shaft, an adjustable lever mounted on the base plate forming an adjustable stop in the path of the oscillating movement of the frame, an operating lever mounted on the base plate engaging with the gear on the shaft, and a diamond carrying lever mounted on the frame having means engaging with the bevel gear pinion for oscillating movement in a plane at about right angles to the oscillating movement of the frame.

4. In a device of the class described in combination with an oscillating frame and a diamond carrying lever oscillating in a plane at right angles to the plane of oscillation of the frame, operating means turnably mounted in the frame so as to cause the oscillating movement of the diamond carrying lever when the frame stands in either of its stopping positions in its oscillating movement.

5. In a device of the class described in combination with an oscillating frame, a diamond carrying lever mounted on the frame so as to oscillate in a plane at about right angles to the oscillating movement of the frame, and operating means mounted concentrically to the oscillating movement of the frame within the frame and engaging with the diamond carrying lever so as to cause the oscillating movement of the lever; a friction member inserted between the operating means and the frame so as to hold the operating means engaged with the frame during the oscillating movement of the frame while the friction member allows the turning of the operating means when the frame comes to either of its terminations in its oscillating movement so as to cause the oscillating movement of the lever in either of the stopping positions of the oscillating movement of the frame.

In testimony whereof I hereunto affix my signature in the presence of two witnesses.

JOSEPH A. STANSBURY.
